UNITED STATES PATENT OFFICE.

RICHARD H. PRICE, OF BOONEVILLE, MISSISSIPPI.

SASH LOCK AND LIFT.

SPECIFICATION forming part of Letters Patent No. 703,465, dated July 1, 1902.

Application filed February 10, 1902. Serial No. 93,399. (No model.)

To all whom it may concern:

Be it known that I, RICHARD H. PRICE, a citizen of the United States, residing at Booneville, in the county of Prentiss and State of Mississippi, have invented certain new and useful Improvements in Sash Locks and Lifts; and I do declare the following to be a full, clear, and exact description of the invention, such as will enable others skilled in the art to which it appertains to make and use the same.

The invention relates to a sash lock and lift.

The object of the invention is to provide a device of this character for use in connection with windows of dwellings and other buildings, which shall be simple of construction, durable in use, comparatively inexpensive of production, and which will permit of the independent adjustment of the upper and lower sashes.

With this and other objects in view the invention consists of certain novel features of construction, combination, and arrangement of parts, which will be hereinafter more fully described, and particularly pointed out in the appended claim.

In the accompanying drawings, Figure 1 is a perspective view of a section of a window-frame, illustrating the application of my invention, the two sashes being shown in closed position. Fig. 2 is a similar view, the lower sash being shown slightly raised. Fig. 3 is a similar view, the upper sash being shown in a lowered position; and Fig. 4 is a vertical sectional view through one of the grips. Fig. 5 is an enlarged detail view of the grips, showing them in operative position.

Referring to the drawings, 1 denotes the window frame or casing, 2 denotes the upper sash, and 3 the lower sash. These parts may be of any well-known or approved construction.

5 denotes a supporting-rod the upper end of which is bent at a right angle to the body of the rod, is screw-threaded, and is adapted to engage the threads of a tubular stud-bracket 6, secured to the upper end of the upper sash 2. This screw-threaded connection of the rod with the bracket enables me to adjust the parts comprising the lock and lift to sashes of different thicknesses.

7 denotes a guide-bracket secured to the upper end of the sash 3, through which said rod projects, and 8 denotes a finger-piece 55 screwed upon the lower end of the rod.

12 denotes a grip secured to the side rail of the lower sash, and 13 denotes a similar grip secured to the side of the window casing or frame. The grip 12 consists of a metal casting or housing 12^a, in which are pivoted gripping-levers 19 and 20, which are held apart in a divergent position by a coil-spring 12^b, which encircles the rod 5. The rod 5 extends through holes formed in the levers 20 65 and 19. The office of the lever 20 in its normal position is to prevent the upward movement of the sash 3, and the office of the lever 19 in its normal position is to prevent the downward movement of said sash. 70

12^c denotes a lip projecting laterally from the base of the housing 12^a for a purpose hereinafter to be described. The grip 13 consists of a housing 13^a, in which is pivoted grip-levers 22 and 23, having apertures 13^c, 75 through which the supporting-rod projects, and these levers are held in divergent position by a coil-spring 13^b, which is placed about said rod and exerts its energy to spread the outer ends of said levers apart. 80

13^d denotes a lip projecting laterally from the top wall of the housing 13^a. This lip is within the path of movement of the grip-lever 20, and the lip 12^c is in the path of movement of the lever 22. In other words, the lip 13^d 85 coacts with the lever 20 and the lip 12^c coacts with the lever 22 to automatically release said levers 20 and 22 from engagement with the rod when the sashes are moved into closed position. 90

The operation of the device is as follows: Assuming the parts to be in the position shown in Fig. 1 and it be desired to elevate the lower sash 3, the grip-levers 19 and 20 are grasped and moved toward each other, thus releasing 95 them from the rod and allowing the sash to be moved upwardly. To move the sash in the opposite direction, these levers are grasped and compressed toward each other, and thus the sash is permitted to lower. When released, the levers exert a binding action upon the rod 5, the lever 19 serving to prevent the downward movement of the sash and the lever 20 serving to prevent the upward move- 100

ment of the sash. To lower the upper sash when the parts are in the position shown in Fig. 1, in which position the grip-levers 20 and 22 are rendered inactive, or, in other words, held from locking engagement with the rod 5 by reason of the fact of the lever 20 engaging the lip 13^d and the lever 22 engaging the lip 12^c of the housings 13^a and 12^b, respectively, the levers 19 and 23 are grasped and compressed toward each other, thus freeing the rod 5 and permitting it to be lowered. By releasing the levers 19 and 23 the sash 2 may be held in any desired adjustment.

From the foregoing description, taken in connection with the accompanying drawings, the construction, mode of operation, and advantages of the invention will be readily understood without requiring an extended explanation.

Various changes in the form, proportion, and details of construction may be made within the scope of the invention without departing from the spirit or sacrificing any of the advantages thereof.

Having thus described my invention, what I claim, and desire to secure by Letters Patent, is—

In a sash lock and lift, the combination with a window-frame and the upper and lower sashes, of a supporting-rod connected at one end to the upper sash, grips, one secured to the window-frame and the other to the lower sash and each provided with spring-actuated grip-levers having holes through which said rod passes and is free to slide, each of said grips having a fixed part projecting into the path of movement of one of the opposing grip-levers whereby the innermost or adjacent grip-levers are automatically unlocked from engagement with the rod when the sashes are in closed position, substantially as set forth.

In testimony whereof I have hereunto set my hand in presence of two subscribing witnesses.

R. H. PRICE.
